ATTORNEYS

UNITED STATES PATENT OFFICE.

THOMAS F. McREYNOLDS, OF PUEBLO, COLORADO.

ATTACHMENT FOR SHOE-STITCHING MACHINES.

Application filed June 8, 1920, Serial No. 387,310. Renewed July 10, 1923.

To all whom it may concern:

Be it known that I, THOMAS F. McREYNOLDS, a citizen of the United States, and a resident of Pueblo, in the county of Pueblo 5 and State of Colorado, have invented certain new and useful Improvements in Attachments for Shoe-Stitching Machines, of which the following is a specification.

My invention relates to improvements in 10 shoe stitching machine attachments, it being more particularly an attachment enabling the ready application of a welt strip, and it consists in the constructions and arrangements substantially as herein described and 15 claimed.

One of the foremost objects of the invention is to provide a guide operating in conjunction with a well known type of shoe stitching machine for the purpose of applying 20 a welt strip either to new or old shoes, as the shoe is manipulated in the stitching operation.

A further object of the invention is to provide a welt strip guide for the purpose of 25 enabling the easy application of a welt strip to old and weakened shoes, thereby at once improving the appearance and adding material strength thereto.

A further object of the invention is to provide an easily and cheaply made attachment 30 for the purpose described.

Other objects and advantages will appear in the following specification, reference being had to the accompanying drawing, in 35 which:—

Figure 1 is a detail view of only so much of a well known type of shoe stitching machine, as is necessary to illustrate the application of the attachment,

40 Figure 2 is a detail perspective view of the welt guide, and

Figure 3 is a detail edge view.

By way of introduction, it is thought desirable to describe the purpose of the invention. There is a type of shoe on the market known as the "Scuffer" shoe which has gained much popularity, especially among children. This is not a welt shoe, but is made by lasting the upper out instead of in, 45 as in ordinary shoes, a small narrow strip of leather being stitched around the upper part of the sole to give it the appearance of a welt shoe.

50 Ordinary shoe repair shops do not have the facilities for repairing this type of shoe, and the result is that the period of useful-

ness of these shoes is somewhat shortened. When attempts to make repairs are made, it becomes necessary to remove the strip referred to above, which strip is sewn on in 60 the factory, thus leaving the stitching too weak to hold the shoe for the subsequent repair operation. Furthermore, in trying to stitch the shoe after the original strip has been removed, on a stitching machine, the 65 awl of the machine will catch behind the original stitch and make the shoe smaller.

The attachment overcomes the difficulties named above, as well as others which might be pointed out. The ordinary shoe guard 70 is removed from its customary place on the stitching machine 1, and the arm 2 of the attachment is secured in its place by the fastening means 3 and slotted end 4. By simply unloosening the fastening means 3 the 75 arm 2 can be pulled off.

The right edge of the arm is slightly bent or curled inwardly as at 5 to impart rigidity to the otherwise flexible metal strip. The leading edge is decidedly offset at 6 to impart additional strength to the arm and make room for the manipulation of the shoe S behind the attachment. The extreme upper end or point of the arm is slightly bent inwardly at 7 for the purpose of holding the 80 welt strip W beneath the sole of the shoe, the shoe being inverted as in Figure 1 during the sewing operation.

Formed at one side of the arm 2 and in continuity with the upper curved edge 8 85 thereof, is the rectangular guide 9 which is of such a size as to easily contain the welt strip and permit its passage without binding. The rough side of the welt strip comes uppermost when threaded into the guide 9 95 as in Figure 2.

The operation can be readily understood. The operator simply inverts the shoe as illustrated in Figure 1, so that the projecting edge of the sole comes over the welt strip 100 W which is to be sewn on. The side of the guide 9 farthest from the observer, bears against the upper of the shoe and thus gauges the distance at which the awl and needle of the stitching machine perforates 105 not only the welt strip but the original sole leather of the shoe. When the welt strip has been sewn on the shoe has the appearance of newness and the strip being of new leather of course gives the shoe additional 110 strength which greatly prolongs its life.

While the construction and arrangement

of the improved attachment as herein described and claimed, is that of a generally preferred form, obviously modifications and changes can be made without departing from the spirit of the invention or the scope of the claim.

I claim:—

An attachment for shoe stitchers, comprising a metal arm having offset edges impart-

ing strength thereto, a slotted lower end enabling attachment, a bent upper point providing a support, and an upper curve in continuation of said bent end, including a rectangular tubular guide through which a welt strip is drawn as a shoe is moved over said guide and bent end during a sewing operation.

THOMAS F. McREYNOLDS.
